UNITED STATES PATENT OFFICE

CHARLES JOVIGNOT, OF MONTROUGE, FRANCE

MEANS FOR SEALING CONTAINERS AND THE LIKE

Application filed January 11, 1928, Serial No. 246,015, and in France November 30, 1926. Renewed April 4, 1931.

The present invention relates to means for applying to jars and other receptacles metal sealing caps having depending flanges with outwardly flaring lower portions in each of which are formed one or more tongues adapted and arranged to be torn off to release the sealing grip of the cap on the receptacle and permit the removal of the closure.

The apparatus according to the invention 10 comprises means adapted to prevent the increase of the peripheral extent of the lower edge of the cap during the sealing operation and means adapted to bring the cap of the flange in sealing contact with the wall 15 of the receptacle.

Other characteristic features of the invention will appear from the following specification and claim with reference to the appended drawings.

20 Fig. 1 is a diagrammatic view showing the aforesaid cap in place upon a vessel and ready for the upsetting operation.

Fig. 2 shows the said cap after the upsetting operation.

25 Fig. 3 shows a device comprising an upsetting sleeve with longitudinal slots.

Fig. 4 shows an upsetting machine utilizing the last-mentioned elastic sleeve and

30 Fig. 5 is the corresponding side view, in which the elastic sleeve is shown in its upper position.

Fig. 6 shows a machine employing an upsetting member consisting of various slidable sectors.

35 Fig. 7 is an elevational view of a modified cap.

Fig. 8 is a section along the line 8—8 of Fig. 7.

40 Fig. 9 shows a jar sealed with the cap of Fig. 7.

Fig. 10 is a section along the line 10—10 of Fig. 9 at a larger scale.

45 Fig. 11 is a similar section along the line 11—11 of Fig. 9.

Fig. 12 is a sectional elevation of a modified form of groove in the sealing apparatus.

50 Fig. 13 is a corresponding partial plan view of Fig. 12.

Fig. 14 is a section along the line 14—14 of Fig. 12.

As shown in Figs. 1 and 2, the flanged part of the cap 1 comprises a cylindrical portion *a* which is preferably knurled, a beading *b* which extends inwardly, and a tapered part *c* whose lower edge is slightly overturned towards the interior at *d*. The said cap may be manufactured by overturning and knurling an ordinary tapered cap at the same time.

For the upsetting operation, the said cap is applied to the receptacle 4 which is suitably held in place. A plastic washer or like packing may be interposed between the upper edge of the receptacle and the top of the 65 said cap, and it will be compressed by the pressure exerted on the cap.

The machine comprises a sleeve 6 which surrounds the said receptacle and can be raised; in this movement, the upper end of 70 the sleeve will drive out the lower overturned part of the cap and will thus bring the tapered part *c* of said cap into a substantially horizontal position, it being folded over upon itself, as shown in Fig. 2. This operation 75 will strongly press the bead *b* of the cap against the outer surface of the receptacle, and the folded part of the cap will thus be made very rigid, whereby the vessel, will be closed in a most reliable manner. The 80 bead *b* need not be continuous, and may consist of variously formed projecting parts.

In the device shown in Figs. 3 to 5, the top edge of the sleeve is cut out at 8 to form a groove in which the tapered part of the cap 85 is engaged, and the sleeve is slotted longitudinally at several points on the circumference, as shown at 9, so as to give it a certain elasticity. In this manner, during the closing operation, the several parts or segments of the sleeve may bend outwardly under the pressure of the flanged part of the cap, so that receptacles having a more or less oval shape or having different diameters may be closed without difficulty and without any special precautions. Despite said elasticity, the sleeve 6 must be rigid enough to bend only when the wall of the receptacle is irregular and to prevent an increase in diameter of the free edge *d* when the wall of the 95 100

receptacle is normal in order to increase the displacement of the bead *b* towards the receptacle.

The said machine comprises an operating lever 10 which actuates—by a cam 12—a piston 13 carrying the upsetting sleeve 6. Through vertical slots of said piston 13 passes a cross-piece 15 secured in the frame of the machine and on which rests a small 10 piston 16 containing a spring 17. The plate 5 holding the vessel to be closed comprises a screw shank carrying a nut and washers (with interposed elastic rings) and rests upon the said spring through the medium of 15 the lower washer. By operating the lever 10; the cam 12 raises the piston 13 and the sleeve 6 until the bottom of the piston 13 engages the bottom of the piston 6. By further operation of the lever 10, the piston 13 20 raises also the piston 16. The vessel carrying its cap, is first applied in an elastic manner against the upper plate 3, and due to the flexion of the spring 17 the sleeve 6 is further raised to the proper extent for the upsetting of the cap.

Fig. 6 shows a modified device which may be employed for the closing of bottles in which the neck is narrower than the body.

In this machine, the upsetting member consists of two semi-circular half-collars 18 having at the interior a groove analogous to the groove 8 in the sleeve 6 above described. The said collars may slide horizontally on the machine along a diameter, when brought together in an elastic manner by the two bell-crank levers 19 which are pivotally mounted at 20 and are pivoted to the rings 21 which may be lowered through the medium of the springs 22 by the rings 23 mounted on the 40 two vertical rods 24. Said rods are connected together at the top by a cross-piece 25 and at the bottom by a shaft 26, and they may be lowered by operating a lever 27 which controls a cam 28 coacting with a roller 29 mounted on the shaft 26. The upper cross-piece 25 carries the top plate 3 by means of the rod 30. The vessel is disposed upon the lower plate 5 which is supported by the machine in an elastic manner by means of a spring 60 in a 50 recess 61 formed in the machine body.

The two half-collars are normally spaced apart, so that the vessel can be readily mounted on the plate 5. By means of the lever 27, the top plate 3 is first brought down so as to press upon the cap, thus compressing the plastic packing if such is used, and to lower the vessel through a certain distance. The two half-collars will then come together by 60 the action of the bell-crank levers, and will exert an elastic pressure upon the neck of the bottle below the cap. The plate 3 continues to descend, and the flange of the cap is thus bent into the groove of the segments, as above 65 explained, whereby the upsetting of the cap

will be effected. The bottle can be disengaged by the inverse operation of the lever.

As shown by the Figs. 7 and 8, the flange of the cap is provided with one or more tongues 50. As indicated previously, the sealing device comprises a sleeve with an annular groove having a tapering side wall 48 and a tapering bottom portion 52.

The bottom portion is provided with one or more recesses 53 corresponding to the number of tongues 50 of the cap and suitably disposed. The annular side wall 48 is provided with corresponding projections 54 adapted each to bear and press on an opposed tongue of the cap. The upper part of the projection 54 is preferably beveled as at 55 joining at its upper edge 56, the upper edge line 57 of the side wall 48. These projections 54 may be formed integral with the side wall 48 of the groove or may be constituted by added parts 58 adequately secured to the sleeve. With said device, during the sealing operation, the flange of the cap will be compressed on all its peripheral extent, except where the tongues are located; these latter will receive a lateral compression from the projections 54 so as to force them in the desired position against the flange of the cap. After the sealing operation the cap presents itself in a general form shown in Figs. 9 and 11. Tearing off one or more tongues will release the sealing grip of the cap on the receptacle and permit the removal of the closure.

Having now described my invention, what I claim as new and desire to secure by Letters Patent is:

An apparatus for closing jars and other receptacles with metal caps having a depending flange, the lower portion of which is flaring outwardly and at least one tongue being provided in said flaring portion comprising a sleeve having an annular groove formed by an annular side wall and a bottom part and adapted to receive the lower edge of said flange and to prevent the increase of the peripheral extent of said lower edge, at least one recess in the bottom part of said groove situated immediately under the corresponding tongue of the cap, at least one projection on said annular side wall of the groove adapted to bear and press on said tongue, means adapted to hold the upper edge of said flange and means adapted to impart a relative motion between said sleeve and said holding means for said upper edge.

In testimony whereof I have signed my name to this specification.

CHARLES JOVIGNOT.
